(57) **CLAIM**

The ornamental design for a hand truck as shown and described.

DESCRIPTION

Applicants are named inventors in currently pending U.S. application Ser. No. 18/378,550, filed Oct. 10, 2023 for an invention entitled “Hand Truck for Securing and Moving Metallic Cylindrical Objects”.

FIG. 1 is a front perspective view of a hand truck showing our new design;

FIG. 2 is a rear perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top view thereof;

FIG. 8 is a bottom view thereof; and,

FIG. 9 is a front view showing a hand truck of our new design in use, with the broken lines depicting a cylindrical object representing environmental subject matter that forms no part of the design to be patented.
